UNITED STATES PATENT OFFICE.

HENRY D. BUCHMAN, OF ALLEGHENY, PENNSYLVANIA.

METHOD OF MAKING MOLDS.

SPECIFICATION forming part of Letters Patent No. 434,104, dated August 12, 1890.

Application filed May 7, 1890. Serial No. 350,929. (No model.)

To all whom it may concern:

Be it known that I, HENRY D. BUCHMAN, a citizen of the United States, residing at Allegheny, in the county of Allegheny and State 5 of Pennsylvania, have invented certain new and useful Improvements in Methods of Making Molds; and I do declare the following to be a full, clear, and exact description of the invention, such as will enable others skilled 10 in the art to which it appertains to make and use the same, reference being had to the accompanying drawings, and to the letters of reference marked thereon, which form a part of this specification.

15 My invention relates to founding, and especially to the preparation of molded molds. In casting articles containing a number of apertures it is frequently a matter of considerable expense, both of time and labor, to 20 make the cores required to produce these apertures and to place them accurately in position in the mold. In the case of cast-iron flanges for metallic pipe a large number of holes must be formed in the flange for the 25 bolts or rivets that unite it to the pipe and to the next flange, and these holes must be all of the same diameter in each and every flange, and since sand cores are destroyed when the casting is removed from the mold 30 it becomes a costly and tedious job to make the great quantity required and to have them all of the same size. My invention is designed to facilitate the molding of such flanges, insuring the accuracy of the rivet- 35 holes both as to position and size, and providing for the rapid duplication of flanges precisely alike in this particular. I accomplish this by the use of the indestructible metallic cores hereinafter described and by 40 my improved method of molding.

In the drawings, Figure 1 is a vertical section of the flask. Fig. 2 is a plan view of the same, partly broken away. Figs. 3 and 4 show my improved metallic core for the rivet-holes. Fig. 5 is a view of the pattern, partly in section. Figs. 6 to 11 illustrate my method of molding, and Fig. 12 is a view of a portion 45 of a pipe and flange.

50 My method is applicable to many kinds of articles; but I will describe it as applied to the production of the flange shown in Fig. 12, which is L-shaped in cross-section and is pro-

vided with a number of rivet or bolt holes in both the face and neck of the flange, the former being that which meets the flange on 55 the adjoining section of pipe and the latter that which is riveted to the pipe. The pattern A that I use is shown in Fig. 5. It is composed of two parts a a' , which separate along a line coinciding with the diameters of 60 the holes a^2 .

I use a three-part flask composed of a cope B, a cheek C C' , and a drag D. They may be of any suitable shape, but are preferably annular. The cope and drag each consist of 65 an outer and an inner ring or wall united by radial cross-bars b d . The cheek consists of an outer ring C, having radial arms c , projecting inwardly. The arms are cut away on the lower and inner sides, thereby forming inverted-L-shaped pieces. The inner wall C' of the cheek is provided with outwardly-projecting short radial arms c' . The several parts of the flask have the usual ears and steady-pins, as shown. The cheek and cope 70 are also provided with clamping-lugs b' c^2 for the clamps B', and all three parts of the flask have diametrically-opposite trunnions, as b^3 , by which they can be suspended and turned over when necessary.

75 The cores that I use for coring the holes in the face of the flange may be of sand, or they may be the same as the one I have invented for coring the holes in the neck of the flange. This is shown in Figs. 3 and 4. It consists of 80 a tube E, of metal or other suitable material, smeared with shellac or other cement and rolled in sand, so as to have a thin coating e of sand adhering to it. The tubes should be strong enough to withstand the pressure of 85 the sand in the mold when rammed and also the weight of the molten iron when poured.

90 My method of forming the mold is as follows, referring to Figs. 6, 7, 8, 9, 10, and 11: The drag is first rammed up and the cores E' 95 for the face of the flange are set in suitable core-prints. (See Fig. 6.) The lower part a' of the pattern is then laid on the pattern-plate F, and the two portions of the cheek C C' are placed one outside and the other inside of it. The cores E are then laid in the holes a^2 , and the upper part of the pattern a is closed down upon them. The cheek is then 100 filled with sand and rammed up, as usual, the

depth of the cheek being such that the top and bottom of the pattern lie flush with the surface of the sand, the cores E being buried in the mold, as shown in Fig. 7. A layer of 5 parting-sand is now spread upon the top of the cheek, and the cope is then placed in position and rammed up, as shown in Fig. 8. It is then removed and set aside temporarily. The upper part *a* of the pattern is then lifted 10 out. (See Fig. 9.) The cope is now replaced on the cheek, and the two are clamped together. They are then inverted, and the lower portion *a'* of the pattern is drawn out, leaving the cores E in position in the sand, as 15 shown in Fig. 10. The cope and cheek are then turned over again to their normal position and placed upon the drag D. The mold is then finished in the usual manner, and is ready for pouring.

20 The heat of the molten metal tends to expand the metallic cores E; but this tendency is expended in contracting the internal bore, leaving the outer diameter unchanged. This is a feature of special importance, since a 25 solid metallic core would increase slightly in size with each pouring, until its value as a gage for the rivet-holes would be entirely destroyed. I am able, however, to use my hollow cores an indefinite number of times with 30 the certainty that the rivet-holes will always be of the same size and conform accurately to gage.

When the mold is broken up, the metallic cores can be easily extracted from the casting, 35 since their thin coating of sand gives them clearance enough for this without impairing their accuracy as gages. They can be quickly made ready for use again by simply coating them anew with sand. By the use of these 40 cores and by my method of molding, in which the cores are rammed up in the mold with the pattern, which is then drawn out without disturbing the cores, I am able to produce large 45 quantities of pipe-flanges or other castings to which this method is applicable at far less cost and with much greater accuracy than by any other means known to me.

In case the cores are made of a material 50 that does not tend to expand under the influence of heat, they may be solid instead of tubular.

Having thus described my invention, what

I claim, and desire to secure by Letters Patent, is—

1. The method of making molds which consists in placing a core between two parts of a separable pattern, ramming them up together in the flask, and then withdrawing the separate parts of the pattern without disturbing the core, substantially as described. 55

2. The method of making molds which consists in placing a separable pattern in a flask whose depth is the same as that of the pattern, inserting the cores in position between the parts of the pattern, ramming up the flask 65 even with the outer faces of the pattern, and withdrawing the parts of the pattern, leaving the cores undisturbed, substantially as described.

3. The method of molding which consists 70 in preparing the drag, placing a two-part pattern in the cheek, with the cores held between the two parts, ramming up the cheek so that the surface of the sand is flush with the top and bottom of the pattern, making a parting, 75 placing the cope upon the cheek and ramming it up, then removing the cope, withdrawing one part of the pattern, replacing the cope, withdrawing the other part of the pattern, leaving the cores undisturbed, and then placing 80 the cope and cheek upon the drag, substantially as described.

4. The method of making L-shaped pipe-flanges having cored rivet-holes, as hereinbefore described, consisting in forming a drag, 85 placing cores therein for the holes in the face of the flange, placing in a cheek a two-part pattern, separable along the line of a series of holes corresponding with those in the neck of the flange, placing between the parts of the pattern a series of indestructible metallic sand-coated cores, ramming up the cheek and cope, withdrawing the two parts of the pattern without disturbing the cores, placing the cheek and cope on the drag, and finishing 95 and pouring as usual, substantially as described.

In testimony whereof I affix my signature in presence of two witnesses.

HENRY D. BUCHMAN.
